UNITED STATES PATENT OFFICE.

DANIEL DODGE, OF KEESEVILLE, NEW YORK.

NAIL-MACHINE.

Specification of Letters Patent No. 25,183, dated August 23, 1859.

To all whom it may concern:

Be it known that I, DANIEL DODGE, of Keeseville, in the county of Essex and State of New York, have invented a new and Improved Feeding and Cutting-Off Apparatus for Wrought Nail and Spike Forging Machines; and I do hereby declare that the following is a full, clear, and exact description of the same, reference being had to the accompanying drawings, forming a part of this specification, in which—

Figure 1, is a plan of a wrought nail machine with the upper or main shaft and its appendages removed. Figs. 2 and 3, are vertical sections both taken very nearly in the same plane indicated by the red line x, x , in Fig. 1, and showing the principal working parts on both sides of such plane. Fig. 4, is a partial transverse section of the machine exhibiting a back view of the cutters. Fig. 5, is a horizontal sectional view or part of the mechanism for operating the gage.

Similar letters of reference indicate corresponding parts in the several figures.

My invention consists in a gripper having the peculiar operation hereinafter described for the purposes of conveying the rod to the forging or pointing apparatus of a wrought nail machine, of holding it during the forging or pointing operation and of conveying it to the cutters which cut off the nails or spikes after they have been forged or pointed.

It also consists in the combination of a gage and cutter or cutters with the aforesaid gripper to operate substantially as herein-after described.

To enable others skilled in the art to make and use my invention I will proceed to describe its construction and operation, but will first explain that though I have represented it applied in connection with a certain kind of forging or pointing machinery I do not consider it any more especially adapted for use with that kind of forging or pointing machinery than with any other, and therefore it will not be requisite for me to refer particularly to any portion of that machinery, further than is necessary to explain my invention.

A, is the main framing of the nail machine.

a, a , are fixed horizontal ways on the said framing for the reception of the slide B, which carries or constitutes a portion of the gripper, the said ways running in a direction to and from the forging or pointing apparatus C, D, E, F, G, H.

On the upper surface of the slider B, is a projection b , which constitutes the lower jaw of the gripper, the upper jaw b' of which is secured by a clamping bolt c , to one end of a spring B', the other end of which is bolted to the slides B, said spring being strong enough to give the jaw b' , the necessary pressure to grip the nail rod (which is represented in red color in Figs. 1 and 2,) with the requisite degree of tightness. By slackening the clamping bolt c , the jaw b' may be adjusted to grip a larger or smaller nail rod.

At the back of the ways a, a , and level with the face of the lower jaw b , there is a stationary rest d , to support the part of the nail rod behind the gripper on its way to the forging or pointing apparatus; and behind this rest d , and some distance in front of the forging or pointing apparatus there are two stationary cutters e, e' , whose edges are horizontal and about level with the face of the rest d , said cutters being at a distance apart equal to the intended length of the nails, the cutter e , being for cutting the nails from the rod and the cutter e' , for cutting any surplus metal from the points of the nails. The said cutters are so applied and secured by keys f, f' , in a part A', of the framing and by a clamp X, as to be capable of adjustment nearer together or farther apart to cut nails of various lengths within certain limits.

Above the cutters f, f' , are two adjustable cutters g, g' , secured by clamping bolts h, h' , to the same arm I', of a horizontal rock shaft I, working in bearings on the top of the framing A, said cutters being intended to operate in combination with e, e' , with a shear like action to cut off the nails. An arm I², of the said rock shaft I, is connected by a rod J, with a spring J, which operates to hold up the cutters g, g' , to such an elevation as to allow the nail rod to pass freely under them until they are desired to have the requisite movement to effect the cutting operation, which is effected by the action on an arm I³, of

the said rock shaft of a wiper K', on the horizontal shaft K, from which all parts of the feeding and cutting-off apparatus derive their action.

5 The shaft K, is arranged in suitable bearings in the main framing A, and derives motion from the main shaft P, of the machine at a greatly reduced speed, through an intermediate shaft Q, and a train of spur 0 gearing M, N, O. A cam K², on the said shaft K, serves to impart a reciprocating motion to the gripper in the ways a, a, through the agency of a three armed rock 5 shaft R, arranged in bearings in the lower part of the front of the framing A, one arm R', of the said rock shaft, being kept in contact with the said cam by means of a strong spring S, connected by a rod S', with its arm R², and its third arm R³, being connected with the slider B, which carries the whole of the gripper. The reciprocating motion thus given to the gripper must be equal to the distance between the position occupied by the finished nail in the forging 5 or pointing apparatus and the position it must occupy over the cutter e, to be cut off. Another cam K³, on the said shaft K, serves to effect the opening of the gripper by its action upon the arm T', of a rocker T, which 0 is arranged in bearings just below the ways a, a, and which has another arm T, projecting forward under a pin i, which is attached to the spring B', of the gripper and which projects downward through an opening 5 in the plate B. Another cam K⁴, upon the same shaft serves to operate the gage V.

The gage V, best shown in Fig. 1, consists of a bent horizontal arm fitted to slide through the head of a vertical shaft W, 0 which is arranged in a suitable bearing or bearings just behind the ways a, a, and on one side of the rest d, and the path of the nail rod. The said gage is secured to the head of the said shaft W, by a clamping bolt j, which on having its nut unscrewed permits the adjustment of the said gage to regulate the feed of the rod. At the bottom of the said shaft W, there is an arm W', which is held against the peripherical 5 face of the cam K⁴, as shown in Fig. 5, by means of a spring k, (Fig. 1) connected with it by a rod l. The movement given to the gage is such as to place it across the path of the nail rod and withdraw it sidewise 0 therefrom at suitable intervals.

The operation of the apparatus is as follows:—At a certain stage in every revolution of the shaft K, the gripper is caused to move outward away from the forging 0 or pointing machinery and when it reaches the outward extremity of its stroke the cutters g, g', strike and immediately rise again out of the way of the rod, and as they re-

turn the gage V, moves into range with the gripper jaws. The rocker T then operates 65 to raise the spring B', and open the jaws of the gripper, but after a moment's interval allows them to close, upon which the gage is immediately moved away out of range with the gripper and the latter approaches the forging or pointing machinery again. An attendant stands in front of the machine with the heated nail rod in his hand and when the gripper opens he pushes the rod through the open jaws and against 70 the gage V. The rod is instantly gripped, and, as the gage moves away is carried forward to the forging or, pointing machinery, to have its end pointed or reduced to the required form and when this has been done 75 the gripper moves back again as before described and places the rod in a suitable position to have the nail cut off by the stroke of the cutter which, immediately after, takes place. The gage is then again placed in 80 range with the grippers and the jaws open to permit the attendant to push forward the rod again ready to be carried forward again by the grippers to forge or point another nail; and this is repeated, the gripper 85 never letting go of the rod except at the front extremity of its stroke and the attendant retaining his hold of the rod, until the metal becomes too cold to be worked, when on the opening of the grippers the rod 90 is drawn out and exchanged for another. The nails when cut from the rod slide down the inclined plane m, (Figs. 2 and 3) and drop through a hole n, in the framing.

The mode of applying and operating the 100 gage and cutters is capable of modification, without departing from the principle of my invention, as for instance, one or both may be made to revolve in a plane perpendicular to and intersecting a line from the gripper 105 to the pointing apparatus, and perform respectively the functions of cutting and gaging at the moment of crossing that line, operating, of course in the same order of succession with respect to each other and to the 110 gripper as above described. The construction of the gripper and mechanism for operating it is also susceptible of modification.

I do not claim generally the use in nail or spike machines, for feeding and gaging 115 the rod and cutting off the nails or spikes of automatic grippers, gages or cutters, or the combination of such automatic contrivances; but

What I claim as my invention and desire 120 to secure by Letters Patent, is—

1. A gripper having a reciprocating movement toward and from forging or pointing machinery, and opening automatically at the outer extremity of its stroke 125 so as to allow the introduction, feeding for-

ward or removal of the rod while it is in this position, but holding the rod fast at every other stage of its operation and while in any other position substantially as herein described.

5 2. And in combination with a so operating gripper, I claim the employment of a

gage and a cutter or cutters operating in the within described order of succession with respect to each other and to the gripper.

DANIEL DODGE.
